UNITED STATES PATENT OFFICE

WALTER J. MULLALLY, OF CHICAGO HEIGHTS, ILLINOIS, ASSIGNOR TO AMERICAN MANGANESE STEEL COMPANY, OF CHICAGO, ILLINOIS, A CORPORATION OF MAINE

EXCAVATING DIPPER

Application filed April 15, 1927. Serial No. 183,870.

This invention relates to the construction of dipper buckets and more particularly to a formation of a bucket in three parts whereby the greater portion of the wear is received by one of said parts which forms an auxiliary front.

Dippers of the type herein described have been commonly cast from manganese steel in two main portions, a front and a back. 10 The parts are adapted to be riveted together along an overlapping seam and the bail brackets have been riveted, in the usual construction, partially to the back and partially to the front whereby the stresses upon the rivets 15 of the side seams are somewhat reduced. The digging lip which forms the forward edge of the front receives the greater amount of the wear and has been sometimes made removable, but ordinarily the dipper teeth themselves are formed with rearwardly extending shanks which form wear ribs protecting the outside of the front. In one design, however, the front has been cast with a double wall 20 having spaced integral truss webs which define sockets, along the front edge of the double wall front, in which the shanks of the dipper teeth may be held. In such a construction the outside wall of the integral double wall front is entirely exposed to wear as 25 it drags on the ground. Therefore, after a period of use the entire front may require replacement. Dipper buckets are now constructed to have a capacity of six or eight yards and such size renders replacement of 30 the entire front in the field impossible.

It is, therefore, the purpose of my invention to so design the bucket construction that the advantages of securing the shanks of the dipper teeth within sockets formed along the 40 forward edge are preserved while, at the same time, the bucket is so constructed that the parts which receive the major portion of the wear may be readily replaced.

In carrying out my general purpose, it 45 is an object of my invention to form the dipper front with a smooth surface both on the inside and outside and to secure an auxiliary front to the main front so that shank-receiving sockets are provided along the forward edge between the two fronts.

It is further an object of my invention to so form the auxiliary front that the forward edge of the main front is protected from wear by an abutting portion or projections from the auxiliary front.

Another object of my invention is to form the auxiliary front with rearwardly extending wear ribs which abut against the outer surface of the main front.

With these and various other objects in view, the invention consists of certain novel features of construction and operation as will be more fully described and particularly pointed out in the specification, drawings and claims appended hereto.

In the drawings, wherein like reference characters are used to designate like parts—

Figure 1 is a side elevation of a dipper bucket provided with the auxiliary front and removable teeth;

Figure 2 is a plan view showing the removable teeth as applied to the auxiliary front sockets;

Figure 3 is a cross section of Figure 2 taken through the auxiliary front sockets and shanks of the dipper teeth;

Figure 4 is a modification of the auxiliary front having a cast integral base and removable points;

Figure 5 is a plan view of a mud lip having fastening portions adapted to be applied in the teeth sockets;

Figure 6 is a modification in section of a particular form of teeth which may be applied to the auxiliary front;

Figure 7 is a section taken through the auxiliary front and dipper front, substantially on line 7—7 of Figure 3; and

Figure 8 is a perspective of another form of tooth adapted to be used with the invention.

Figure 1 shows the general construction comprising the back A, connected to a main front B, the forward outer portion of which is covered by the auxiliary front C and having the usual door D pivoted to the back A. The main front B is provided with a latch E of ordinary construction adapted to latch the door D.

More particularly, the dipper bucket 1 is

provided with the usual front 2, the connection between the dipper back and front being by suitable fastening means through a lapped joint as shown in Figure 3. An auxiliary front 3 is riveted or otherwise secured by suitable means 20 to the dipper front, and said auxiliary front may conveniently be provided with the dipper bail bracket 21 which, in the form shown, is also riveted or fastened to the dipper front by means of the rivets 20. It has been found preferable to secure the bails to the front through the auxiliary front, there being the advantage in this construction that the stresses incident to work are eliminated from the connecting seam of the main front and the back of the dipper, as can be readily appreciated. The auxiliary front 3 is recessed at suitable intervals as at 7 and is provided with spacers or 20 ribs 4^a forming sockets adapted to support dipper teeth or lip shanks. Said auxiliary front is provided with a front contacting and fastening portion 5 which is integral with the sockets and supports the bail bracket. 25 The front may be also reinforced by the provision of rearwardly extending webs 18 from the auxiliary front which cover a portion of the outside of the main front and receive the wear. As will be evident from Figure 2, 30 the ribs extend generally in line with the dipper teeth 4.

It will further be evident from Figures 2 and 7 that the auxiliary front is provided with upward projections 19 which cover the forward edge of the main front between the dipper teeth, thus together with the projections which are formed integral with the teeth, the entire forward edge of the main front is covered against wear. In a modification later to be described in which a tooth base is formed integral with the auxiliary front, the projections 19 are in the form of a continuous abutment extending along the forward edge of the main front, see Figure 45 7, instead of being separated, as shown in Figure 2. Besides forming a wear protection for the main front, the projections 19 prevent the entire stress from falling on the fastening rivets 8.

50 As shown in Figure 7, the recesses 7 of Figure 3 are really of double formation as indicated at 14, in the direction of the length of the teeth, and provide spacing members 15 through which the auxiliary front rivets 8^a are adapted to pass to fasten the auxiliary front to the dipper front. It will further be seen that the auxiliary front is here provided with inwardly projecting portions (not numbered) which engage the main front. 55 With such construction, it will readily be appreciated that shearing stresses are eliminated from the rivets 8^a, any stresses incident to work being transmitted to the main front by the projecting portions.

60 In the modification shown in Figure 4, the

auxiliary front is provided with a toothed base 13 cast integral and provided with suitable lugs 13^a which are adapted to support the removable points 9 through any suitable fastening means, such as bolt 12.

70 Any form of tooth may be used in the sockets provided by the auxiliary front, such as the form shown in Figure 6, wherein in the tooth 4 there is provided a lightening core 4^d extending back into the shank 4^b of the tooth, said tooth being fastened by the usual rivet 8; but it will be understood that any tooth, such as that shown in Figure 8, 75 may be used wherein no lightening cores are provided, the tooth taking the usual form having shoulders 16 and 17 for contact with the front and auxiliary front respectively, thereby taking shear off of the fastening rivets 8 which extend through the usual hole 11^c provided in the shank 4^b. A mud lip 80 may be provided, such as 4^e, shown in Figure 5 as straight, but it will be understood that said lip may conveniently be formed of arcuate or any other shape, the lip being provided with a plurality of shanks 10 provided with rivet holes 11, which shanks are adapted to fit in the sockets formed in the auxiliary front and fastened by usual rivets 8.

85 It will be seen that from the construction shown that the three-piece dipper is perfectly smooth on the inside, there being no projections, such as dipper teeth or lips, to extend therein; therefore, there will be free and easy passage of the material through the dipper. It will also be seen that the reinforcing ribs which form the sockets form strength members such as to prevent the main front from bulging out of shape or wearing. In case any teeth are broken or it is desired to transform the dipper from stone to mud work, it is only necessary to remove the rivets 8 which hold the teeth and replace said teeth with other teeth or the mud lip. This is particularly desirable as it is simple, the main parts of the dipper do not have to be removed, 90 and the work may be performed in the field without the necessity of having machines to handle the heavy parts of the dipper.

95 From my description it will be apparent that buckets of large size may be easily designed and cast in three parts and, in use, the main front will be protected to a large extent from receiving wear in digging operation, primarily due to the construction of the auxiliary front in such a manner that the usual digging lip of the main front is covered. The auxiliary front may be readily replaced in the field.

100 It is to be understood that the modifications shown are merely by way of illustration and not by way of limitation as many and various forms will occur to those skilled in the art.

105 I claim:

110 1. In a device of the character described, 130

the combination of a dipper front, an auxiliary front, said auxiliary front having reinforcing ribs or spacers abutting the main front, means formed integral with said auxiliary front for protecting the forward edge of the main front and removable scraping means disposed between the front and auxiliary front.

2. In a device of the character described, the combination of a dipper front, an auxiliary front, said auxiliary front having reinforcing ribs or spacers abutting the main front, means formed integral with said auxiliary front for protecting the forward edge of the main front, removable scraping means disposed between the front and auxiliary front, and having shoulders cooperatively engaging said front and auxiliary front whereby shearing stresses are removed from the fastening rivets.

3. In a dipper, the combination of bucket forming members, a closure supported by said members, an auxiliary front carried by one of said members and having portions forming sockets therewith, extensions on said auxiliary front contacting with the member carrying said front, projections formed integral with said auxiliary front adapted to form the digging edge of the dipper and scraping means supported in said sockets.

4. In a dipper, the combination of bucket forming members including a front, a ribbed member secured to said front with the ribs thereof in socket forming relation with said front, said member having projections engaging said front to thereby relieve securing means between said front and member of shear.

5. In a dipper construction, a main front having a smooth inner surface, an auxiliary front attached to the outside of said main front, said auxiliary front provided with ribs abutting said main front whereby shank-receiving sockets are formed, means forming a digging lip integral with said auxiliary front and covering the forward edge of the main front.

6. In a dipper construction, a main front, an auxiliary front attached to the outside of said main front, said auxiliary front having a forwardly and upwardly projecting portion adapted to abut against the forward edge of the main front and receive the wear, and dipper teeth received between said main and auxiliary fronts.

Signed at Chicago Heights, Illinois, this 7th day of April, 1927.

WALTER J. MULLALLY.
